United States Patent Office

Des. 178,708
Patented Sept. 4, 1956

178,708

SHOPPING CHECK

William F. Tydings, Detroit, Mich., assignor to Francis Burr Company, Detroit, Mich., a partnership

Application October 11, 1954, Serial No. 32,620

Term of patent 3½ years

(Cl. D59-6)

Fig. 1 is a front view of a shopping check showing my new design;

The back of the check is blank and without design features.

I claim:

The ornamental design for a shopping check, as shown and described.
